CLAIM

The ornamental design for a hair brush handle, as shown and described.

DESCRIPTION

FIG. 1 is a perspective view of a hair brush handle showing my new design.

FIG. 2 is another perspective view thereof.

FIG. 3 is a front or rear view thereof.

FIG. 4 is a right side view or left side view thereof.

FIG. 5 is a top view thereof; and,

FIG. 6 is a bottom view thereof.

The broken lines in the drawings depict features that form no part of the claimed design.
